CLAIM

The ornamental design for a bottle, as shown and described.

DESCRIPTION

FIG. 1 is a top, front, left side perspective view of a first embodiment of a bottle embodying the new design;

FIG. 2 is a left side elevational view thereof;

FIG. 3 is a right side front elevational view thereof;

FIG. 4 is a front elevational view thereof;

FIG. 5 is a back elevational view thereof;

FIG. 6 is a top plan view thereof;

FIG. 7 is a bottom plan view thereof;

FIG. 8 is a top, front, left side perspective view of a second embodiment of a bottle embodying the new design;

FIG. 9 is a left side elevational view thereof;

FIG. 10 is a right side front elevational view thereof;

FIG. 11 is a front elevational view thereof;

FIG. 12 is a back elevational view thereof;

FIG. 13 is a top plan view thereof;

FIG. 14 is a bottom plan view thereof;

FIG. 15 is a top, front, left side perspective view of a third embodiment of a bottle embodying the new design;

FIG. 16 is a left side elevational view thereof;

FIG. 17 is a right side front elevational view thereof;

FIG. 18 is a front elevational view thereof;

FIG. 19 is a back elevational view thereof;

FIG. 20 is a top plan view thereof; and,

FIG. 21 is a bottom plan view thereof.

The dash-dash-dash broken lines of a pour spout and thread in the FIGS. 8-13 drawing views are included for the purpose of illustrating environmental structure and form no part of the claimed design.

The dot-dash-dot-dash broken line shown in the FIG. 21 drawing views defines the bottom boundary of the claimed design and forms no part thereof.

1 Claim, 15 Drawing Sheets
